UNITED STATES PATENT OFFICE.

CHARLES F. MEILINK, OF TOLEDO, OHIO.

FIRE-RESISTING STRUCTURE.

Application filed July 19, 1920. Serial No. 397,274.

To all whom it may concern:

Be it known that I, CHARLES F. MEILINK, a citizen of the United States of America, residing at Toledo, Lucas County, Ohio, have 5 invented new and useful Fire-Resisting Structures, of which the following is a specification.

This invention relates to fire resisting housings.

10 This invention has utility when incorporated in metal bound insulation carrying structures, as so-called fire-proof safes.

Referring to the drawings:

Fig. 1 is a perspective view of a fire proof 15 safe embodying features of the invention;

Fig. 2 is an enlarged fragmentary section on the line II—II, Fig. 1;

Fig. 3 is a fire proof safe joint view similar 20 to Fig. 2, showing enlarged joint recesses or chambers; and

Fig. 4 is a portion of a stepped member.

A fire resisting housing is herein disclosed in a fireproof safe having outer sheet metal 25 wall 1 and inner sheet metal wall 2, as a

double walled structure for a chamber 3. An opening 4 to the chamber 3 may be closed by door or closure member having outer wall 5 mounted by hinges 6 to swing the door from the housing 1. This door has an inner

30 wall 7 connected to the door outer wall 5 by a stepped portion 8 interfitting with stepped portion 9 between the housing outer wall 1 and the housing inner wall 2. To

35 dam or impede the travel of heat from within out to the chamber 3 by way of the joint at the portions 8, 9, such joint may carry at the step or projecting portions packing 10, 11, and 12, which as herein disposed provides chambers or dead air spaces 13, 14, at the

40 joint. This packing 10, 11, 12 may be yieldable, and heat resisting, as asbestos tape, having its surface coated, say with enamel or finished similarly to the re-entrant portions of the joint, and as so assembled not

45 only checks heat radiation inward, but seems in practice to dissipate or otherwise retard heat conductivity along the sheet metal portions 8, 9.

Further means is herein provided, which 50 in practice has seemed to drive back or check effectively temperature rise in the chamber 3. A simple embodiment of this means comprises vents or opening means 15 at the joint. These vent means may be normally sealed

against slight resistance by paint or enamel 55 coating 16. Between the double walls 1, 2, and 5, 7, of the structure, there is introduced an asbestos and magnesia composition as a heat insulation filler. In practice this filler is given a definite body with water, molded 60 into position, and then kiln dried out, so that there is left therewith no free water, although it does contain or include H_2O chemically combined or associated in some hydrate form. After the kiln drying, the 65 walls 1, 2, as a metal sheathing for the filler may be painted, coated, or given the finish, which may normally seal the vents 15 by carrying thereover the film 16. When subjected to extreme heat, say above 250° F., 70 this heat insulation filler 17, may give off a vapor of steam, creating a pressure of a few ounces between the double walls of the structure and oozing through vents 15, by rupturing the films 16. This moist vapor has a 75 very marked action in throwing back, or resisting inward travel of temperature rise by way of the joint. While the joint region is of minor extent, these vents may serve as nozzles in conducting the steam as a quenching medium into such joint. With the further provision of the air pocket or chamber 14 as a receiver for the steam, the heat checking value of this vapor is conserved for most 80 prolonged high temperature exposures, as to higher heat and longer duration than the Underwriters' Laboratories normal specifications for fireproof safes. These underwriters' tests have to do with the temperature rise within the safe when the safe is exposed 85 for a specified interval to definite heat.

Fig. 3 shows joint walls 8, 9, with the filler 17 recessed near the steps to form enlarged pockets or chambers 20, 21. There is thus permitted a greater capacity vapor 90 receiver in the joint for checking inflow of temperature.

This retarding of heat travel has great utility in making practicable much lighter construction, with thinner walls for less filler 100 therebetween, to withstand or resist a rise in temperature for a given period of time. In fact the housing thickness may be reduced about one third, thereby producing a superior fireproof safe of less weight and using 105 less material. The operation is automatic when the emergency of a fire arises, and the sealed in filler 17, is not corrosive nor hy-

grosscopic for swelling or other form of deterioration in the period of normal use of the safe.

What is claimed and it is desired to secure 5 by Letters Patent is:

1. A double walled housing provided with an opening, a rigid non-absorbent wall closure for the opening providing a joint, and a filler for the housing carrying moisture, releasable by heating for vapor escape 10 into said joint, said housing having vent means from between the double walls into the joint for the passage of the vapor in its escape into the joint.
- 15 2. A non-absorbent double walled housing provided with an opening, a closure for the opening providing an air chamber forming joint with the housing, and a vapor carrying heat insulation filler for the housing, said 20 housing having vent means from between the double walls into the joint as vapor escape ways to said air chamber.
- 25 3. A double walled metallic housing provided with a stepped opening, a closure for the opening stepped to interfit with the housing opening to form an air chamber therebetween, and a heat insulation filler carrying moisture escapable therefrom to said chamber, said housing having vent means 30 from between the double walls into said chamber for the passage of moisture in its escape to said chamber.
- 35 4. A double walled sheet metal housing

provided with a stepped opening, a double walled closure for the opening stepped to 35 interfit with the housing opening, packing means coacting at the joint between the opening and housing to seal an air chamber in the joint, and a heat insulation filler capable of giving off water vapor upon heating into said air chamber.

5. A double walled sheet steel housing provided with an opening a stepped jamb for the opening having vents thereinto, a closure for the opening and having a stepped frame 45 coacting to provide a chamber adjacent the vents, a hinge for mounting the closure upon the housing, said frame and jamb having the stepped portions thereof curved for close clearance in the swinging of the closure toward and from the opening, and a filler capable of giving off vapor upon heating to flow into the chamber through the vents.

6. A double walled housing provided with a stepped opening, a closure for the opening 55 stepped to interfit with the housing opening in forming a joint and providing an air chamber in said joint, packing between the closure and housing yieldable to seal the chamber, normally sealed vent means in communication with the chamber, and a filler capable upon heating to give off a vapor and generate a pressure to unseal the vent means and enter said chamber.

In witness whereof I affix my signature.

CHARLES F. MEILINK.
